CLAIM

The ornamental design for a laser level detector, substantially as shown and described.

DESCRIPTION

FIG. 1 is a perspective view of an embodiment of a laser level detector according to the invention.

FIG. 2 is a front elevational view of the embodiment.

FIG. 3 is a rear elevational view of the embodiment.

FIG. 4 is a left elevational view of the embodiment.

FIG. 5 is a right elevational view of the embodiment.

FIG. 6 is a top elevational view of the embodiment; and,

FIG. 7 is a bottom elevational view of the embodiment.

The broken lines which define the bounds of the claimed design form no part thereof.
